ABSTRACT OF THE DISCLOSURE

A swimming pool formed in the ground in which the sides of the excavated ground provide a form against which a foam, such as urethane foam, may be sprayed, the foam constituting the wall of the pool. The foam may be sprayed in a first less dense layer and then in a second more dense layer. The foam may be covered with a liner such as a vinyl liner.

Background of the invention

Field of the invention.—In-ground fabricated swimming pools.

Description of the prior art.—Swimming pools known to the art which are fabricated in the ground include spraying concrete against the wall of an excavated hole in the ground. Such known pools utilize the structural integrity of the concrete to maintain the strength of the pool. It is usually, if not always, necessary to provide re-enforcing rods or re-enforcing mesh upon which the concrete is sprayed.

Summary of the invention

It is an object of the present invention to provide a swimming pool which is easily and inexpensively fabricated and easily and inexpensively maintained.

It is another object of the present invention to provide a swimming pool which may be fabricated in virtually any shape or configuration on one continuous piece including extensions for steps, edging and the like.

It is a further object of the present invention to provide a swimming pool which, although durable, is nonetheless subject to extremely simple and durable repair. Repair may be any of several procedures, including respraying of an affected area, patching of an affected area through the use of adhesive secured patches, heat secured patches or solvent secured patches, or the like.

It is a still further object of the present invention to provide a thermally insulative swimming pool.

It is another further object of the present invention to provide a swimming pool having a not insubstantial degree of resiliency which provides a substantial safety feature.

Basically, but not by way of limitation, the present invention comprises the spraying against the sides of an excavated hole in the ground of a rigid or semi-rigid foam such as urethane foam. The foam may be sprayed in layers with the inner layers (those farthest from the ground) being of a higher density than the outer layers (those adjacent the ground). A liner, such as a vinyl plastic liner, may be applied to complete the inner surface of the pool.

Brief description of the drawing

In the drawing:

FIGURE 1 is a pictorial representation of the swimming pool of the present invention shown with water therein.

FIGURE 2 is a cross-sectional view as taken across line 2—2 of FIGURE 1, but without the water.

FIGURE 3 is an enlarged fragmentary cross-sectional view of the wall of the swimming pool.

2

Description of the preferred embodiment

The swimming pool 10 of the present invention comprises an earth supported wall 12.

5 Wall 12 comprises a bottom or outer layer 14, an upper or inner layer 16 and a surface covering 18. Outer layer 14 and inner layer 16 may both be made or formed of the same or similar material. Surface covering 18 is preferably a smooth waterproof material, such as vinyl, which could be renewable or replaceable.

10 Outer layer 14 is preferably a relatively lighter density urethane foam and inner layer 16 is preferably a relatively higher density urethane foam, the term urethane being intended to include the polyurethanes.

15 Swimming pool 10 of the present invention is fabricated in the following manner:

An excavation in the size and shape desired for the pool is created. The first or outer layer 14 is sprayed to a substantially uniform thickness against the side of the excavation. The spray is continued up over the edge 20 of the excavation to form a suitable edging. Then the second or inner layer 16 is sprayed against outer layer 14 to a uniform thickness. The first or outer layer 14 cures in contact with the earth and the second or inner layer 16 cures in contact with outer layer 14.

25 The result is a continuous one-piece pool wall 12 of great integrity and strength. The earth defining the side of the excavation acts as a form for the sprayed foam. If, in accordance with standard outdoor pool practice, 30 water is left in the pool during freezing and below freezing conditions, little if any damage will result to wall 12 as a result of frost heaves or co-efficients of thermal expansion. Among the reasons for these outstanding features is the fact that the outer layer 14 binds the surface of the adjacent earth and also is the fact of the resiliency 35 of the foam material utilized.

It has been determined that a functionally superior pool results from spraying a higher density inner layer 16 than outer layer 14. It is conceivable that the actual spraying 40 of the foam material may proceed in a continuous process from the outer portions adjacent the earth with foam of lesser density to the inner layer with foam of greater density.

45 Resistance to wear and a smoother more water resistant and dirt resistant pool surface may be obtained by lining the pool with a vinyl liner, either sprayed, painted, laid in film or sheet form, or the like. A polyester resin may also be used.

The limitations upon the depth and shape of the excavation and pool depends to a great extent upon the 50 nature and composition of the ground. It may be necessary in soils to lower clay content, for example, to bias inwardly a deeper wall of the excavation. Such a construction is shown on the right side of FIGURE 2 wherein at the deep end of the pool the end wall extends vertically downward for a distance and then, to prevent collapse of the excavation, curves or biases inwardly.

55 Swimming pool 10, when constructed in accordance with the foregoing, embodies numerous advantages and 60 features which are not attainable with conventional methods or materials. For example, wall 12 is resilient. There is far less likelihood of physical injury to a user of the pool whether through design, such as diving, or from dereliction, such as horseplay, there is substantial and abrupt contact with the wall of the pool.

65 Although pool 10 has great structural integrity, being without seams or other weak portions, it will of course require repair from time to time. Repair may be accomplished in the simplest of manners. For example, should 70 a surface crack appear in wall 12 repair may be effected by the use of a solvent for the foam utilized. Should a larger fissure occur, repair may be effected by the use of

a patch or by simple respraying of the affected area. Surface covering 18 is easily renewed by recoating. Other repairs are as easily accomplished.

While the foregoing is illustrative of a preferred embodiment of this invention, it is clear that other embodiments and modifications may be had. For example, it may be desirable to place an intermediate member adjacent the sides of the excavation and to spray the foam against the member. While the foam may thereby be prevented from binding the soil during curing, the advantages may be realized. The intermediate member conceivably could be vapor or moisture barrier. The intermediate member conceivably could be used for local reinforcement, as to provide attachment points for accessory apparatus, or for general reinforcement, as to provide for unusual conditions. The intermediate member conceivably could be fluid, such as an oil spray or an adhesive coating. Also for example, the foam utilized depends upon choice and circumstances. A polyurethane foam, or the use of a plurality of foams is not without contemplation.

What is claimed is:

1. An in-ground swimming pool, comprising:
  - (a) an earthen form, said earthen form excavated to a desired configuration; and
  - (b) a foam wall member, said foam wall member being contiguous with said earthen form, said foam wall member comprising:
    - (i) an outer foam layer; and
    - (ii) an inner foam layer.

2. An in-ground swimming pool in accordance with claim 1, wherein said foam wall member is made of urethane foam.

5 3. An in-ground swimming pool in accordance with claim 1, wherein said inner layer is of a relatively higher density than the density of said outer layer.

4. An in-ground swimming pool in accordance with claim 3, wherein said inner layer is provided with a surface liner.
